SEAR MECHANISM FOR GUNS

Clarence F. Hofstetter, Missoula, Mont.

Application June 17, 1932, Serial No. 617,776

8 Claims. (Cl. 89—27)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a sear mechanism for guns.

In fixed machine guns mounted on aircraft and adapted to fire between the blades of the propeller it is customary to employ a trigger motor, 10 synchronized with the motor driving the propeller, for actuating the sear of the gun.

The principal object of this invention is to provide a sear mechanism of the type described which may be applied to existing breech bolts 15 without requiring modification thereof, and which will be positive in action while necessitating the application of only a slight force to operate the same.

The present invention is characterized by a 20 novel method of moving the sear into engagement with the firing pin, of locking and unlocking the sear, and controlling the locking means.

To these and other ends, the invention consists in the construction, arrangement and combination of elements described hereinafter and pointed out in the claims forming a part of this specification.

A practical embodiment of the invention is 30 illustrated in the accompanying drawing, wherein:

Fig. 1 is a longitudinal sectional view through the receiver of a gun and showing a part of the breech bolt in section.

Fig. 2 is a longitudinal sectional view of the 35 rear end of the breech bolt showing the arrangement of the parts with the firing pin in cocked position.

Fig. 3 is a view similar to Fig. 2 with the firing pin in fired position.

Figs. 4 and 5 are views in rear elevation of the 40 bolt corresponding respectively to Figs. 2 and 3.

Fig. 6 is a view in front elevation of the slide.

Figs. 7 and 8 are views respectively in rear 45 and front elevation of the sear.

Fig. 9 is a plan view of the spring for the slide.

Referring to the drawing by numerals of reference there is shown the receiver frame 5 of a machine gun within which a bolt 6 is reciprocally mounted. Within the bolt is a longitudinally disposed firing pin 7 normally urged in a forward direction by means of a spring 8 housed in the firing pin and seated on a vertical pin 9 passing through the bolt. The firing pin is cocked in a well known manner by the lever 10 when the bolt moves in recoil.

The firing pin is held in cocked position by means of a sear 11 which, with only a slight modification, is the sear provided on the Browning machine gun, many of which are now in service. This sear is mounted for vertical sliding movement in a slot 12 in the rear end of the bolt and is formed with ribs 13 on its opposite sides which fit in grooves 14 in the side walls of the slot. The sear includes a forwardly projecting arm 15 formed with a transverse shoulder 16 centrally on its upper face. This shoulder is adapted to engage a shoulder 17 formed by recessing or grooving the under side of the firing pin adjacent its rear end. The shoulders 16 and 17 are complementarily inclined so that the firing pin in moving forward under the influence of its spring may exert a camming action to depress the sear.

The upper portion of the rear end of the firing pin is beveled to provide a cam surface 18 adapted to act on an inclined surface 19 of the lug 20 on the front face of the sear whereby the sear is automatically raised during cocking of the firing pin to bring the shoulders 16 and 17 into engagement.

The sear is held in the raised or locking position by means of a slide 21 mounted in a transverse slot 22 in the rear end of the bolt at one side of the slot 12 and having ribs 23 on its opposite sides working in grooves 24 in the walls of the slot. The connection between the sear and slide is effected by means of a square lug 25 on the rear face of the sear and the surfaces provided by a channel 26 in the front face of the slide. The channel is formed with a stepped floor, the upper step 27 adapted to engage the lug 25 and hold the sear in the elevated position whereby to lock the firing pin in cocked position and the lower step 28 adapted to engage the lug and limit depression of the sear when the firing pin moves forward as shown in Fig. 5.

The slide is normally maintained in the sear-locking position, Figs. 2 and 4, by means of a flat spring 29 secured to the pin 9 and having its extremity disposed in a slot 30 in the top rib 23. The spring moves the slide to the left, its action being limited by the left side wall of the slot 12. Movement of the slide to the right is limited by engagement of the inner end of the slide with the right hand wall of the slot 12. An offset 31 intermediate the length of the spring 29 is disposed in a recess 32 in the bolt and serves to hold the spring in engagement with the slide as well as to prevent withdrawal of the pin 9.

In Figs. 2 and 4 the shoulder 16 on the arm 15 of the sear is engaging the shoulder 17 of the firing pin which is in cocked position and the sear is prevented from being lowered relative to the firing pin by virtue of the engagement of its lug 25 with the upper step 27 in the slide 21. The slide is maintained in the locking position by the spring 29. When the slide is moved to the right the lug 25 is free to be moved downwardly to the lower step 28. The sear is depressed through the action of the firing pin, being cammed down due to the action of the shoulders 16 and 17 when the firing pin is moved forward under the influence of its spring 8.

Downward movement of the sear is arrested when the lug 25 rests on the lower step 28. In this position the lug 25 opposes the return movement of the slide.

As the bolt moves in recoil the cocking lever 10 retracts the firing pin and compresses the firing pin spring. The cam surface 18 on the firing pin acts on the inclined surface 19 of the lug 20 and elevates the sear to the position shown in Fig. 2 with the shoulder 16 of the arm 15 engaging the shoulder 17 of the firing pin. The lug 25 on the sear is now in the upper part of the channel 26 in the slide and the slide is free to be moved to the left by its spring 29 to position the upper step 27 underneath the lug.

I claim:—

1. In a gun, a breech bolt, a firing pin having a beveled upper rear end and a shoulder on its under side adjacent the rear end, a firing pin spring, means for cocking the firing pin, a vertically movable sear carried by the bolt, an arm on the lower end of the sear having a shoulder engageable in front of the shoulder on the firing pin, a lug on the front face of the sear engageable by the beveled rear end of the firing pin to elevate the sear, a lug on the rear face of the sear, a transversely movable slide mounted in the bolt and having in its front face a channel with a stepped floor, the lug on the sear positionable in said channel, and a spring normally holding the slide in a position where the floor of the upper step in the channel will engage the lug on the rear face of the sear.

2. In a gun, a breech bolt, a firing pin movable relative to the bolt, a firing pin spring, means for cocking the firing pin, a vertically slidable sear carried by the bolt and engageable with the under side of the firing pin, a lug on the sear engageable by the rear end of the firing pin whereby it is cammed upwardly by the firing pin when the firing pin is cocked, a lug on the rear face of the sear, a transversely movable slide mounted in the bolt and having in its front face a channel with a stepped floor, the lug on the sear positionable in the channel and means normally holding the slide in a position where the floor of the upper step in the channel will engage the lug on the sear.

3. In a gun, a breech bolt, a firing pin movable relative to the bolt, a firing pin spring, means for cocking the firing pin, a vertically movable sear carried by the bolt and engageable

with the under side of the firing pin, means on the sear whereby it is cammed upwardly by the firing pin when the firing pin is cocked, a transversely movable slide in the bolt, means on the slide for holding the sear in raised position and releasing said sear when the slide is moved, means on the slide for limiting downward movement of the sear and a spring for normally moving the slide into a position where the first mentioned means is operative.

4. In a gun, a breech bolt, a firing pin movable relative to the bolt, a sear for holding the firing pin in retracted position, means on the sear whereby it is cammed upwardly by the firing pin into position of holding engagement therewith, a slide movable transversely of the sear, means on the slide for maintaining the sear in holding engagement with the firing pin, and means on the slide for supporting the sear when it is out of engagement with the firing pin.

5. In a gun, a breech bolt, a firing pin movable relative to the bolt and having a beveled upper rear end, a sear vertically slidable in the breech bolt for holding the firing pin in retracted position, a lug on the sear engageable by the beveled rear end of the firing pin whereby it is cammed upwardly by the firing pin in position of holding engagement therewith, and a slide movable transversely of the bolt for maintaining the sear in holding engagement with the firing pin.

6. In a gun, a breech bolt, a firing pin movable relative to the bolt, a sear vertically slidable in the breech bolt for holding the firing pin in retracted position, a beveled lug on the sear engageable by the rear end of the firing pin whereby it is cammed upwardly by the firing pin in position of holding engagement therewith, and means for maintaining the sear in holding engagement with the firing pin.

7. In a gun, a bolt, a firing pin in the bolt, a firing pin spring, a pin passing through the bolt and seating the firing pin spring, a lever for cocking the bolt, a sear carried by the bolt and engageable with the firing pin to hold it in cocked position, a slide movable transversely of and engageable with the sear to hold it in engagement with the firing pin, and a spring carried by the pin and positioned adjacent the cocking lever, said spring acting on the slide to normally hold it in engagement with the sear.

8. In a gun, a bolt having a groove, a firing pin in the bolt, a firing pin spring, a pin passing through the bolt and seating the firing pin spring, a lever for cocking the bolt, a sear carried by the bolt and engageable with the firing pin to hold it in cocked position, a slide movable transversely of and engageable with the sear to hold it in engagement with the firing pin, and a spring carried by the pin and positioned adjacent the cocking lever, said spring acting on the slide to normally hold it in engagement with the sear and having a portion normally disposed in the groove of the bolt.

CLARENCE F. HOFSTETTER.
